PACKAGING MACHINE, PARTICULARLY
THE BLOCKS THEREFOR

Pasquale Carrino, Passaic, N. J.

Application January 21, 1947, Serial No. 723,326

2 Claims. (Cl. 93—44)

1

My invention relates to an improvement in packaging machines and particularly to that type of machine wherein formed boxes or other containers are fed through the machine and in their passage are lined.

More specifically my invention is directed to packaging machines wherein the lining material is formed or shaped in the machine, inserted into the container and then the lined container is discharged from the lining station.

Still more specifically my invention is directed to an improvement in packaging machines wherein the container liners are formed successively about a series of members commercially known as "blocks," these blocks advancing into register successively with the containers to be lined, where the container and liner are caused to telescope each other while the liner is still in place on the block. The lined container is then allowed to fall by gravity away from the block.

This is conventional practice, and this general type of packaging machine is in wide use.

I might go further and mention that the lined containers are then advanced to a filling station, filled with whatever material is being packaged, sealed, and discharged from the machine ready for shipment, all in a continuous operation.

These machines are very complicated and are fully automatic in operation, so that it is very important that their operation be as nearly perfect and fool-proof as possible.

In my experience with these machines extending over a period of several years I have found considerable difficulty in obtaining proper discharge of the lined containers from the blocks, despite the fact that it is quite usual to attach the lining to the container by the use of a suitable adhesive. In forming the liners the lining material is shaped on the blocks, fitting the same fairly snugly so that there is a decided reluctance for the liners to leave the blocks as the containers are to be discharged from the blocks. The condition appears to be aggravated when the atmosphere of the room where the machine is being operated is too warm although trouble is experienced even in cool weather. Under warm conditions, when a waxed paper is being employed for the liners, there is a tendency for the lining material to become tacky and to cling to the block. A certain amount of the wax of the paper will cling to the block so that eventually the machine becomes clogged and must be stopped in order that the block or blocks may be cleaned. Despite all precautions and warnings the attendant at such a machine

2

will often try to free the block while the machine is running. This is dangerous practice and may result in the loss of a hand or arm.

One of the objects of my invention is to improve the construction of these blocks whereby these difficulties are overcome, my improved block being a decided improvement over existing structures even when lining material which is not of a sticky or tacky nature is employed. 10 in that regardless of the lining material employed my improved construction promotes the easy, rapid and sure discharge of the lined containers from the blocks.

More specifically my invention provides a construction wherein when the blocks carrying the lined containers progress to the discharging station the blocks are reduced in dimension so as to be drawn away from the liners, allowing the container with its liner to fall away from the block.

As will be brought out in the detailed description to follow, I have shown a block which is generally rectangular in cross section. I wish it to be understood that this is merely illustrative and 15 not by way of limitation, in that the invention is not limited to this one specific shape. It will be appreciated also from the description to follow that while but one side of the block is made collapsible this too is for illustrative purposes only.

Inasmuch as packaging machines of the general type to which my invention relates are a well known article of commerce, I have deemed it unnecessary to illustrate a complete machine, 20 my drawings for purposes of clarity being confined to that part of the machine in which my invention has been incorporated.

In the accompanying drawings, Fig. 1 is an elevational view of a packaging machine block embodying my invention;

Fig. 2 is a similar view of the block of Fig. 1, showing the block turned through 90°.

Fig. 3 is a section on the line 3—3 of Fig. 2;

Fig. 4 is a fragmentary view of the block of Fig. 1 showing the block contracted or collapsed;

Fig. 5 is a fragmentary elevational view of a part of a packaging machine at the station where the lined containers are discharged from the blocks; and

Fig. 6 is a view on the line 6—6 of Fig. 5.

Referring to the drawings in detail, 2 designates the blocks of a packaging machine, these blocks being carried, as is customary practice, on an endless, driven chain 4.

As above pointed out, in machines of this gen-

eral type the liners for the containers 6 are formed in the machine directly about the blocks.

The unlined containers are advanced in spaced relation to the spaced blocks 2 by a suitable conveyer 8 equipped with suitable supports 10 upon which the containers rest. The arrangement is such that as each container advances into proximity to a liner, on one of the blocks 2 the container and liner will telescope each other to line the container. This is illustrated at the extreme left in Fig. 5 where the container and liner have been brought together into container-lined position.

The lower lead of the chain 4 and upper lead of the conveyer 8 are traveling from left to right as viewed in Fig. 5.

Upon further advance of the container and block the lower end of the container overlaps a stationary platform 12, and leaves the conveyer support 10. The further advance of the chain 4 advances the container and liner assembly to the discharge station where the lined container drops upon a conveyer belt 14 which carries it to filling equipment (not shown) where the boxes are filled, sealed and discharged from the machine.

As above explained difficulty is experienced in these machines with effecting the certain discharge of the lined containers 6 from the blocks 2. This is particularly troublesome on warm days and where the lining material is inclined to be tacky. The difficulty is due, apparently to the liner actually sticking to the block because of its tendency to tackiness or to the close conformity of the liner to the shape of the blocks, the liners being formed directly on the blocks with the blocks functioning as a form therefor, or both of these factors may contribute to the difficulty. It must be borne in mind also, that the lower end of the container is closed which also has a tendency to prevent ready sliding of the lined containers off the blocks.

Inasmuch as the entire machine is automatic in operation, it will be appreciated that clogging of the machine, due to failure of the lined containers being discharged properly, will slow up the entire machine and necessitate stoppage of the machine. Then again there is the danger of an attendant attempting to clear the machine without shutting it down.

In order that the many difficulties and drawbacks above referred to in a general fashion may be overcome, I have provided the construction best illustrated in Figs. 1 to 4.

Referring to these figures in detail, it will be seen that each block has been shown as substantially rectangular in cross section, and is equipped at one end with suitable formation 16 whereby it may be secured to the chain 4.

It is to be understood that the shape of the block will depend upon the shape of the container to be lined; as will be appreciated by those skilled in this art.

Interiorly of the block, and mounted for oscillation in the block ends is a rod 18, preferably flat at least on one face as shown at 20.

Fastened to the flat face 20 of this rod are two angle irons 22 and 24 adjacent the inner and outer ends of the block.

The side 26 of the block facing the angle irons 22 and 24 is milled out or formed with a rectangular slot which receives an elongated member 28 slidable laterally transversely of the block as viewed in Fig. 1.

This member 28 is slotted adjacent its inner

and outer ends as seen at 30 for the reception of the outer ends of plates 32, attached to 28 by pins 34. These plates extend toward the rod 18, and the inner end of each of these plates 32 is attached to the base of each of the angle irons 22 and 24 by pins 36. By this arrangement oscillation of the rod 18 will effect lateral movement of the laterally slidable elongated member 28 toward and away from the axis of the block.

Secured to the outer face of the member 28 is a flat plate 38 which functions as the side of the block, this plate being secured to the member 28 by screws 40 or in some other fashion so that the two are rigid and immovable with respect to each other.

Rigidly secured to the inner end of the rod 18 is an actuating arm 42 projecting at right angles to the rod and carrying a roller 44. A spring 46 is attached to the arm 42 and to some fixed part of the block.

It will be seen from the description thus far given that if the rod 18 be rotated against the action of the spring 46, the plate 38 will be drawn inwardly of the block, to contract the block as illustrated in Fig. 4, and that upon release of the rod 18 the parts will be restored to the position illustrated in Fig. 1.

Reverting to Figs. 5 and 6 of the drawings, it will be seen that 48 designates a cam secured to the frame of the machine in position to be engaged by a roller 44 of actuating arm 42 as each block comes up to the discharge station for the lined containers.

From all of the foregoing it will be appreciated that as the lined containers leave the supports 10 of conveyor 8, they will be transferred by the blocks 2 to the platform 12. As they are advanced along this platform by the blocks, each container is engaged successively by a roller 50 which bears against the face of the container and is driven from any suitable power source and cooperates with a roller 52 carried by the block. Further advance of the block brings the roller 44 into engagement with the stationary cam 48 contracting the plate or side 38 of the block thereby to draw this side away from the lining entirely to permit the lined container to drop upon the conveyor 14. After the block passes the cam 48 the spring 46 will restore the block to its original dimensions. It should be noted, and as illustrated in Fig. 4 that the block is so constructed that on contraction the plate 38 moves inwardly an appreciable distance beyond the plane of the block face and that on expanding the plate moves outwardly a short distance beyond the block face. I have found from experience that this is desirable in that I am assured the plate 38 will move out of contact with the container liner.

It will be seen from all of the foregoing that I have provided an arrangement for promoting discharge of the lined containers from the blocks of a packaging machine and that my construction is simple and positive in its operation.

It will be appreciated by those skilled in this art that the trouble so prevalent in this general type of machine of failure of the lined containers to discharge properly is eliminated with the elimination of machine stoppages from this cause.

While I have illustrated and described a specific embodiment of my invention, it is to be understood that changes may be made in the details of construction and arrangement of parts as if-

lustrated and described within the purview of my invention.

It is to be understood also, that another and several sides of the block may be contracted and expanded without departing from the spirit and scope of the invention.

It is to be understood furthermore, that blocks other than those which are rectangular in cross section fall within the scope of my invention.

What I claim is:

1. In a packaging machine, the combination of a series of blocks, each carrying a container liner; means for telescoping each block and container liner with a container; forwarding means for forwarding the telescoped blocks and containers successively to a discharge or unloading station, one side of each block being movable bodily laterally, inwardly and outwardly, relative to the block; a rotatable member within each block, attached to the movable block side and extending to the block exterior; a cam-operated arm carried by each rotatable member; and a cam at the discharge or unloading station engaged successively by said arm to rotate said rotatable member to move the side of each block inwardly thereby to facilitate discharge of the lined containers from the blocks.

2. In a packaging machine, the combination of a series of blocks, each carrying a container liner; means for telescoping each block and liner with a container; forwarding means for forward-

ing the telescoped blocks and containers successively to a discharge or unloading station, one side of each block being laterally movable bodily, inwardly and outwardly, relative to the block; a rotatable member within each block attached to said bodily movable side and extending to the block exterior; a cam-operated arm carried by each rotatable member; a cam at the discharge or unloading station engaged by each arm as each block arrives at the discharge or unloading station, whereby the arms will be deflected successively to actuate the movable side of each block inwardly of the block, thereby to prevent clinging of the container liner to the block and facilitating removal of the lined containers from the blocks; and means for restoring the block side to its original position when its arm advances out of contact with the cam.

PASQUALE CARRINO.
